(57) CLAIM

The ornamental design for a light, as shown and described.

DESCRIPTION

FIG. 1 is a bottom perspective view of a first embodiment of a light, showing my new design in a pendant; FIG. 2 is a top perspective view of the first embodiment; FIG. 3 is a front elevation view of the first embodiment; FIG. 4 is a top plan view of the first embodiment; FIG. 5 is a bottom plan view of the first embodiment; FIG. 6 is a top perspective view of a second embodiment of a light, showing my new design in a pendant; and, FIG. 7 is a bottom perspective view of the second embodiment.

Portions of the light are shown in broken lines. Portions shown in broken lines form no part of the claimed design. The break lines shown in the drawings indicate that the appearance of any portion of the article between the break lines forms no part of the claimed design. The jagged broken lines form no part of the claimed design.
